US00D851718S

(12) **United States Design Patent** (10) Patent No.: **US D851,718 S**
Stokke et al. (45) Date of Patent: ** Jun. 18, 2019

(54) **GOLF CLUB HEAD**

(71) Applicant: **KARSTEN MANUFACTURING CORPORATION**, Phoenix, AZ (US)

(72) Inventors: **Ryan M. Stokke**, Anthem, AZ (US);
David A. Higdon, Cave Creek, AZ (US)

(73) Assignee: **Karsten Manufacturing Corporation**, Phoenix, AZ (US)

(**) Term: **15 Years**

(21) Appl. No.: **29/639,236**

(22) Filed: **Mar. 5, 2018**

(51) LOC (11) Cl. **21-02**

(52) U.S. Cl.

USPC **D21/747**

(58) **Field of Classification Search**
